MOUNTING FOR OSCILLATORY MEMBERS

Paul N. Martin, Penn Township, Allegheny County, Pa., assignor to The Union Switch & Signal Company, Swissvale, Pa., a corporation of Pennsylvania

Application December 26, 1942, Serial No. 470,266

3 Claims. (Cl. 200—166)

My invention relates to a mounting for oscillatory members, and particularly to a mounting for the contact fingers, armatures or other oscillatory parts of electrical relays and similar devices.

One object of my invention is to provide a mounting which will absorb a minimum amount of operating force, and which at the same time is sufficiently rugged for practical handling in production.

According to my invention, the mounting comprises a relatively thin flexible supporting member secured at its opposite ends to a support and to the oscillatory member, and disposed with all but a relatively short amount of its length between two relatively stiff reinforcing members spaced at one end from the supporting member by a spacing member which causes the supporting member to flex in a gradual curve through a relatively large part of its length, whereby the whole assembly has a resulting action similar to a stiff member supported on a hinge pin without the objection of possible sticking and the relatively higher cost of a hinge pin arrangement.

Other objects and characteristic features of my invention will become apparent as the description proceeds.

I shall describe several forms of mountings embodying my invention, and shall then point out the novel features thereof in claims.

In the accompanying drawing,

Fig. 1 is a side elevational view showing a mounting embodying my invention applied to an electrical contact. Fig. 2 is a view similar to Fig. 1 but showing the parts in a different position. Figs. 3 and 4 are fragmentary views showing modifications of the mounting means illustrated in Figs. 1 and 2. Fig. 5 is a back view showing a mounting embodying my invention applied to the armature of the usual tractive type of relay. Fig. 6 is a sectional view taken on the line VI—VI of Fig. 5.

Similar reference characters refer to similar parts in each of the several views.

Referring first to Figs. 1 and 2, the reference character 1 designates a fixed contact finger and the reference character 2 designates a movable contact finger which cooperates with the fixed contact finger 1 to form an electrical contact 1—2. The fixed contact finger 1 may have any preferred construction. As here shown it comprises a flexible strip 1a of suitable conducting material such as phosphor bronze riveted at one end to a rigid supporting strip 1b, and provided at the other end with a low resistance contact member 1c consisting of a carbon block. The supporting strip 1b is moulded into a block 3 of suitable insulating material such as a phenol condensation product, and has riveted thereto below the flexible strip 1a a curved strip 1d which acts

as a stop to position the flexible strip when the contact formed by the two contact fingers 1 and 2 is open.

The movable contact finger 2 is constructed in accordance with my present invention, and comprises a relatively thin flexible strip 2a riveted at one end to a rigid supporting strip 2b moulded into the block 3 in a manner similar to the strip 1b of the finger 1. The free end of the strip 2a is disposed with all but a relatively short amount of its length contiguous to the supporting strip 2b between two reinforcing strips 2c and 2d which are riveted to the strip by means of spaced rivets 2e. The rivets 2e also serve to fasten to the finger 2 a low resistance contact member 2f for cooperation with the low resistance contact member 1c of the finger 1. The low resistance contact member 2e may have any desired construction, but as shown it consists of a U-shaped strip of silver or silver laminated material. The reinforcing strips are bent outwardly away from the strip 2a at the ends next to the supporting strip 2b, and secured to the strip 2a between the diverging ends of the reinforcing strips is a double headed rivet 2g which acts as a spacing member, and which permits the flexible strip 2a to flex uniformly in the form of a gradual curve through a relatively large part of its length when the movable contact finger is moved toward or away from the fixed contact finger to engage or disengage the low resistance contact members 2f and 1c. The necessary movement of the finger 2 to engage or disengage the low resistance contact members 2f and 1c may be accomplished in any desired manner. As illustrated, the finger 2 is arranged to be moved by an insulating operating member 4 provided with a laterally projecting pin 5 carrying an insulating thimble 6. The thimble 6 extends between and cooperates with bifurcations 2h and 2i secured to the free end of the finger 2 by means of certain ones of the rivets 2e which secure the reinforcing strips to the flexible strip 2a. The insulating operating member 4 may be operated manually or may be connected to the armature or other movable member of a relay, as will be readily understood.

As shown in Fig. 1, the parts occupy the positions they occupy when the contact is open, and under these conditions, the flexible strip 2a is unflexed. When it is desired to close the contact, the operating member 4 is moved upwardly to the position in which the contact member 2f engages the contact member 1c as shown in Fig. 2. This movement of the operating member causes the flexible strip 2a to flex uniformly in a gradual curve throughout substantially all of that part of its length extending from the point where the strips 2c and 2d start to diverge to the point where the strip 2a joins the strip 2b, and it will be seen therefore that the whole assembly of the

movable finger has a resulting action very similar to a stiff member supported on a hinge pin without the objections of possible sticking and high cost of the hinge pin arrangement.

It should be particularly pointed out that due to the fact that the flexible strip 2a is relatively thin and is caused to flex through a relatively large part of its length, very little deflecting force is required to operate the contact. Furthermore, in spite of the use of the relatively thin strip 2a, 10 with the consequent low deflecting force required and the low fibre stress produced in the strip, the whole contact finger assembly is sufficiently rugged for practical handling in production because of the very short unsupported length of the 15 flexible strip 2a. It will be apparent, of course, that the flexing of the strip 2a causes a slight sliding action between the rivet 2g and the diverging ends of the reinforcing strips.

A contact finger embodying my invention is 20 particularly suitable for, although in no way limited to, use in plug-in relays of the type described and claimed in Letters Patent of the United States No. 2,198,704, granted to Branko Lazich on April 30, 1940. In relays of this type, a relatively large number of contact fingers are provided, and the efficiency of the relay as a whole depends to a large extent upon the operating force required to move the movable contact 25 fingers. With the contact fingers constructed in the manner described, this operating force is reduced to a minimum without any substantial increase in cost and without any decrease in the reliability of the relay.

If desired, the possible distortion of the thin flexible strip 2a due to rough handling, as in the shipment of the relay, may be further reduced by extending the diverging ends of the reinforcing strips 2c and 2d to the point where they overlap the adjacent end of the supporting strip 2b, as shown in Fig. 3.

In Fig. 4 I have shown an alternate method of spacing the thin flexible strip 2a from the diverging ends of the reinforcing strips 2c and 2d, which method consists in providing the diverging ends of the reinforcing strips with small curved offset portions 2j and 2k which contact the opposite side of the strip 2a directly opposite each other.

Referring now to Figs. 5 and 6, I have here shown mounting means embodying my invention arranged to support the armature 7 of a relay. The relay is of the well-known direct current tractive type, and comprises in addition to the armature 7 an electromagnet B consisting of a pair of parallel cores 8 connected at their upper ends by a back-strap 9 and provided at their lower ends with enlarged pole pieces 10.

The mounting means for the armature 7 comprises two relatively thin flat strips 11 and 12 of resilient material such as phosphor bronze, the upper ends of which are secured to the one edge of the armature in parallel spaced relation by means of screws 13 and clamping blocks 14. The lower ends of the supporting strips are each disposed between two reinforcing strips 15 and 16, and are secured by means of screws 17 and 18 to a supporting bracket 19 of non-magnetizable material such as brass, which latter, in turn, is fastened to the sides of the pole pieces 10 by 70 means of screws 20. The strips 11 and 12 extend upwardly in a plane disposed substantially at right angles to the plane of the pole faces 10a of the pole pieces 10, and the reinforcing strips 15 and 16 have their upper ends bent outwardly 75

away from the strips 11 and 12 to permit the desired flexing of the strip as explained below. Secured to each of the strips 11 and 12 between the diverging ends of the associated reinforcing strips 15 and 16 is a double headed rivet 21 which acts as a spacing member and which causes the flexible strips 11 and 12 to flex uniformly in the form of a gradual curve through a relatively large part of their lengths in response to movement of the armature 7 toward or away from the pole pieces 10.

One advantage of the mounting means shown in Figs. 5 and 6 is that it restrains the armature from appreciable motion horizontally without the necessity for any additional guiding means.

Another advantage of the mounting means shown in Figs. 5 and 6 is that since only a relatively short length of the strips 11 and 12 is non-supported these strips can be made thin enough to require very little deflecting force to bend them in the direction to permit the desired movement of the armature.

Although I have herein shown and described only a few forms of mountings for oscillatory members embodying my invention, it is understood that various changes and modifications may be made therein within the scope of the appended claims without departing from the spirit and scope of my invention.

Having thus described my invention, what I claim is:

1. A mounting for an oscillatory member comprising a fixed support, a relatively thin flexible spring member secured at its opposite ends to said support and to said oscillatory member and disposed with all but a relatively short amount of its length between two relatively stiff reinforcing members secured to said oscillatory member and each spaced at one end from said spring member by spacing means which permits said spring member to flex through a large part of its length.

2. A movable contact finger comprising a fixed supporting member, a relatively thin flexible strip secured at one end to said supporting member and having all of its free end but a relatively short portion adjacent to said supporting member secured between two reinforcing members which are secured to said oscillatory member and which diverge away from said strip, a contact member secured to the free end of said finger and a spacing member secured to said flexible strip between the diverging ends of said reinforcing members and acting to cause said strip to flex through a relatively large part of its length in response to movement of the free end of said finger.

3. A movable contact finger comprising a relatively thin flexible strip secured at one end to a supporting strip and having all of its other end but a relatively short portion adjacent to said supporting strip disposed between two reinforcing strips which are secured to said other end of said flexible strip, said reinforcing strips being spaced from said flexible strip at the ends adjacent to said supporting strip, a double headed rivet secured to said flexible strip between the spaced ends of said reinforcing strips and cooperating therewith to cause said flexible strip to flex in a gradual curve throughout a large part of its length when said other end of said flexible strip is moved, and a low resistance contact member secured to said strip for cooperation with the contact member of a cooperating contact finger.

PAUL N. MARTIN.
